(57) **CLAIM**

The ornamental design for a reflective vehicle safety drape, as
shown and described.

DESCRIPTION

FIG. 1 is an isometric view of a reflective vehicle safety drape;
FIG. 2 is front view thereof, wherein a rear view is a mirror
image of the front view;

FIG. 3 is a left-hand side view thereof, wherein a right-hand
side view is a mirror image of the left-hand side view;

FIG. 4 is a top view thereof; and,

FIG. 5 is a bottom view thereof.
